[57] CLAIM

The ornamental design for a mailbox, as shown and described.

DESCRIPTION

FIG. 1 is a front perspective view of a mailbox showing my new design;

FIG. 2 is a front view;

FIG. 3 is a top view;

FIG. 4 is a bottom view;

FIG. 5 is a right side view;

FIG. 6 is a rear side view; and,

FIG. 7 is a left side view thereof.

The broken line showing of the support in FIGS. 1,2,4,5,6,7 is for illustrative purposes only and forms no part of the claimed design.
